UNITED STATES PATENT OFFICE.

ALBERT P. McGLINCHY, OF LINCOLN, NEBRASKA.

AUTOMATIC GREASE-PLUG LOCK.

1,082,091.

Specification of Letters Patent. Patented Dec. 23, 1913.

Application filed July 13, 1912. Serial No. 709,290.

To all whom it may concern:

Be it known that I, ALBERT P. McGLINCHY, citizen of the United States, residing at Lincoln, in the county of Lancaster and State of Nebraska, have invented certain new and useful Improvements in Automatic Grease-Plug Locks, of which the following is a specification, reference being had therein to the accompanying drawing.

10 This invention relates to automatic grease plug locks, and has for its object the production of a grease plug especially adapted to be used upon locomotive engines, or other places where the continual jar would tend 15 to cause the plug to become loose or to rotate.

The principal object of this invention is the production of an efficient lock which will efficiently engage the adjustable plug 20 in such a manner as to hold the same against accidental rotation.

Another object of this invention is the production of an efficient pawl mechanism which is simple in construction, and consists 25 of a comparatively small number of parts for holding the grease plug against accidental rotation.

With these and other objects in view, this 30 invention consists in general of certain novel details of construction, combinations and arrangements of parts, as will be hereinafter fully described and claimed.

In the drawings, Figure 1 is a perspective 35 view of the grease plug. Fig. 2 is a rear elevation of the grease plug. Fig. 3 is a vertical section thereof. Fig. 4 is a transverse section taken through the grease plug just above the locking pawl.

By referring to the accompanying drawings, it will be seen that the plug comprises 40 the socket 1 which is provided with a lower externally threaded end 2, which end is adapted to be threaded into an aperture formed in the desired portion of the machinery for attaching the plug for lubricating purposes. The plug 1 is provided with flattened portions 3 for facilitating the adjustment of the plug 1 by means of the wrench or gripping mechanism. The socket 45 1 is internally threaded, and within this internally threaded socket is adjustably mounted a feeding plunger 4, which plunger is threaded so as to be vertically adjustable in the socket 1 as the feeding plunger 4 is 50 rotated. The feeding plunger 4 is provided with a vertically extending neck 5 which is

provided upon its sides with a plurality of vertically extending grooves 6, which grooves extend the entire length of the neck 5.

A plurality of spaced ears 7 are formed upon the socket 1, as indicated in Figs. 1 and 4, and a locking pawl 8 is pivotally mounted between these ears 7 by means of the pivot pin 9. This locking pawl 8 is provided with a contacting finger 10, which contacting finger is adapted to engage one of the longitudinally extending grooves 6 for holding the plug 5 against rotation when it is desired to hold the plug in a locked position. This pawl 8 is provided upon its lower end with an enlarged knuckle portion 11, which knuckle portion is provided with a socket 12. A coil spring 13 has one end seated in the socket 12 formed in the knuckle portion 11, and the other end of the spring 13 is fitted in the socket 14 formed in the socket or base 1 of the plug. It will be seen that this coil spring 13 will exert an outward pressure upon the pawl and thereby force the projecting finger 10 in engagement with the vertically extending slot 6 formed in the upwardly extending neck 5. The pawl 8 is provided upon its upper rear end with a plurality of transversely extending groove portions 15 for constituting roughened surfaces for facilitating the withdrawing of the pawl 8 from the notches 6 of the plunger 4.

From the foregoing description it will be 90 seen that a very efficient and durable device has been produced whereby the vertical plunger of the gravity feed grease plug will be held against accidental rotation which would cause the lubricant to be fed when it 95 was unnecessary to do so, or cause the plunger to become entirely lost from the socket 1. There has thus been provided a simple and efficient device of the kind described, and for the purpose specified.

Having thus described the invention, what is claimed as new, is:—

An automatic grease plug comprising an internally and an externally threaded body portion, a collar formed integral with said body portion and provided with a socket formed in the periphery thereof, a pair of spaced ears formed integral with said body and extending above said collar, a threaded plunger adapted to be rotated in said body 110 and provided with a plurality of vertically extending grooves, a locking pawl pivotally

mounted between said ears and provided with a depending knuckle having a pocket portion in alinement with the socket formed in said collar, a coil spring positioned in 5 said socket and said pocket, said depending knuckle of said pawl constituting means for protecting said spring, said pawl provided with a finger portion adapted to engage one of the grooves of said plunger and said 10 finger portion provided with a plurality

of transversely extending finger engaging grooves at its rear end for facilitating the withdrawal of said finger from said vertically extending grooves of said plunger.

In testimony whereof I hereunto affix my 15 signature in presence of two witnesses.

ALBERT P. McGLINCHY.
